COMPARTMENTED JACKET FOR BOOKS OR THE LIKE

Herbert S. Chase, Woodmere, N.Y., assignor to Bernard Cahn Co., Inc., New York, N.Y.

Application May 21, 1958, Serial No. 50,993

Term of patent 14 years

(Cl. D6—2)

The rear of the compartmented jacket for books or the like is identical in appearance to the front shown.

I claim:

The ornamental design for a compartmented jacket for books or the like, substantially as shown and described.
